DEVICE FOR RECEIVING AND DISCHARGING MEASURED QUANTITIES OF LIQUID

Rudolf Hebeisen, Wohlen, Aargau, Switzerland

Application October 7, 1933, Serial No. 692,597
In Switzerland April 18, 1932

5 Claims. (Cl. 4-30)

The present invention relates to means for receiving and discharging measured quantities of liquid, for instance, a flushing apparatus for sanitary closets. The known flushing devices for sanitary closets are all provided with a float which acts as the control device. Flushing devices involving the use of a float do not, however, answer modern requirements inasmuch as they frequently get out of order and require almost continuous repair and attendance.

The subject of the present invention is free from these disadvantages and consists substantially in a device for the reception and discharge of a predetermined, but variable quantity of liquid, for instance, water. The liquid is taken from a pressure conduit and may be used for any purpose, more particularly for flushing a sanitary closet.

The improved device according to the invention consists of a completely closed container adapted to receive the liquid direct from a pressure conduit, and provided with a liquid discharge valve which is not controlled by a float, but is controlled by the liquid within the container.

One embodiment of the invention is shown by way of example in the accompanying drawing in a sectional elevation.

In the drawing 1 indicates the liquid discharge valve which, as previously stated, is not controlled by a float, but is controlled by a quantity of liquid contained in a cylinder 2 communicating with the main liquid container. The liquid to be discharged in predetermined quantities enters a completely closed main container 4 from a pressure conduit (not shown) through the admission union 3. A baffle 5 is arranged above the point of entry of the liquid, that is, above the union 3, in order to reduce the noise which might otherwise be caused by the entering liquid. A valve casing 11 is fixed to the container, such casing being provided with an interior cylinder 2, preferably cast with the casing in one piece. In the cylinder 2 works a piston 6 provided with a piston ring 7 and rigidly connected by a piston rod 8 with the main discharge valve 1. The main discharge valve 1 controls the main discharge opening 9 of the container 4. The piston rod 8 is guided in a conical cover 10 of the cylinder 2. Between the cylinder 2 and the wall of the valve casing 11 is provided a hollow space 12 for the discharge of the liquid from the main container. Below the bottom 13 of the cylinder 2 and at right angles to the axis of the casing 11, a bore 14 is provided in the valve casing 11, in

which is arranged the control device 15. In the wall portion 17 of the valve casing 11 is formed a passage 18 extending parallel to the axis of the casing and reinforced by a rib 16. The liquid can pass from the main container 4 through port 19 and passage 18 into the horizontal bore 14 and acts thereon upon a valve 20, the pressure upon that valve being therefore equal to the pressure within the container 4. The valve 20 is provided with a packing 21 in order to ensure a tight closing, and is rigidly connected with a rod 22, a spring 24 tending to move the valve against its seat 23. A packing gland 25 serves for obtaining a tight sliding joint. By means of a lever 26 acting upon the control member 15 and the rod 22, the valve 20 may be moved away from its seat against the action of the spring 24. The liquid which has passed through the passage 18 into the bore 14 passes when the valve 20 has been moved away from its seat, into an annular space surrounding a reduced portion 27 of the rod 22 and therefrom through a cross bore 28 into the cylinder 2 below the piston. The piston is then exposed to the same pressure as the valve 1 over the main discharge opening 9, but as the piston has a greater area than the area of the valve 1, the piston 6 rises in the cylinder 2 until it reaches a stop 29 formed by the lower edge of the cover. By the movement of the piston 6, the valve 1 is also lifted through the piston rod 30 and the main discharge opening 9 is uncovered. The liquid now descends from the main container between the wall of the valve casing 11 and the cylinder wall 30, flows around the transverse valve casing 31 and into the discharge union 32. As soon as this discharge has been started, the hand operated lever is released. The rod 22 now returns under the action of the spring 24 into its initial position, and the valve 20 closes the flow of the liquid into the cylinder 2. At the same time, the rod 22 uncovers a passage 33 and consequently the water quantity under the piston can flow through the passage 28 around the reduced portion 27 of the rod 22 and the passage 33 into the discharge union 32. Owing to the discharge of the water, the piston 6 descends and with it also the valve 1, the latter closing at the end of its downward movement the main discharge opening of the container 4. A regulating screw 34 serves for varying the cross section of the passage 33 and the time within which the water is discharged from below the piston 6. In this manner the quantity of water discharged from the container 4 is regulated. If the cylinder 2 is discharged more slowly, the valve 1 re-

- mains a longer time open and consequently the main container will feed a discharge pipe 35 connected to the discharge union until the cylinder is completely emptied. When the discharge of 5 the main container 4 commences, additional water can flow from the pressure pipe into the container. The cross section of the supply pipe should be considerably smaller than the cross section of the discharge.
- 10 After the closing of the main valve 1, water will flow from the pressure pipe into the container through the union 3 until the pressure in the container 4 and in the pressure pipes become equal.
- 15 I claim:
1. A device for receiving and delivering measured quantities of liquid, comprising in combination: a closed container adapted to be supplied with liquid from a pressure conduit and to 20 discharge liquid, but otherwise being completely closed; a port for supplying said closed container with liquid under pressure; a baffle above said port for the purpose of silencing the admission of liquid in the said container; a main discharge conduit for discharging liquid from said closed container; a main discharge valve for controlling the discharge of liquid from said closed container into said main discharge conduit; and means for controlling said main discharge valve comprising 25 in combination: a cylinder arranged within said main discharge conduit; a conduit for admitting liquid from said closed container to said cylinder; a conduit for discharging liquid from said cylinder; a set screw for varying the cross sectional 30 area of said last named discharge conduit, said set screw being operable from the outside; a piston adapted to work in said cylinder, said piston being directly connected with said main discharge valve; and a manually operable valve for 35 controlling the admission and discharge conduits of said cylinder, substantially as described.
  2. A device for receiving and delivering measured quantities of liquid, comprising in combination: a closed container adapted to be supplied 40 with liquid from a pressure conduit and to discharge liquid, but otherwise being completely closed; a discharge conduit for discharging liquid from said closed container; a main discharge valve for controlling the discharge of liquid from 45 said container through said discharge conduit; means for controlling said main discharge valve operable by a predetermined portion of the liquid within said closed container and by a manually operable control valve, said means for controlling 50 said main discharge valve comprising: a cylinder; a piston associated with said main discharge valve and adapted to work in said cylinder; a piston rod on said piston; a cover on said cylinder effecting complete closure thereof and adapted 55 to serve as a guide for said piston rod; a conduit for supplying liquid from said closed container to said cylinder; a conduit for discharging liquid from said cylinder; means for adjusting the cross section of said last-mentioned discharge conduit; and a hand-operable valve for controlling the conduits associated with said cylinder, substantially as described.
  3. A device for receiving and delivering measured quantities of liquid, comprising in combination: a closed container adapted to be supplied 60 with liquid from a pressure conduit and to discharge liquid, but otherwise being completely closed; a discharge conduit for discharging liquid from said closed container; a main discharge 65 valve

valve for controlling the discharge of liquid from said container through said discharge conduit; means for controlling said main discharge valve operable by a pre-determined portion of the liquid within said container and by a manually operable control valve, said means for controlling said main discharge valve comprising: a cylinder; a piston associated with said main discharge valve and adapted to work in said cylinder; a piston rod on said piston; a cover on said cylinder adapted to effect complete closure thereof and to serve as a guide for said piston rod; a conduit for supplying liquid from said closed container to said cylinder; a conduit for discharging liquid from said cylinder; means for adjusting the cross section of said last-mentioned discharge conduit; and a hand-operable valve for controlling the conduits associated with said cylinder, said valve comprising a longitudinally extending 70 slid able member adapted to close said discharge conduit.

4. A device for receiving and delivering measured quantities of liquid, comprising in combination: a container provided with an inlet and an outlet for liquid, but otherwise completely closed, 75 said container being completely filled by a quantity of pressure water located at its lower part and a quantity of pressure air located at its upper part; a discharge conduit for discharging liquid from said closed container under liquid and air pressure; a main discharge valve for controlling the discharge of liquid from said container through said discharge conduit; means for controlling said main discharge valve operable by a predetermined portion of the liquid within said closed container and by a manually operable control valve; and a pressure liquid admission conduit adapted to admit liquid to said container through the inlet, whereby the air in said container is compressed above the pressure water 80 and forms a compressed air cushion, substantially as described.

5. A device for receiving and delivering measured quantities of liquid, comprising in combination: a container provided with an inlet and an outlet for liquid, but otherwise completely closed, 85 said container being completely filled by a quantity of pressure water located at its lower part and a quantity of pressure air located at its upper part; a discharge conduit for discharging liquid from said closed container under liquid and air pressure; a main discharge valve for controlling the discharge of liquid from said container through said discharge conduit; means for controlling said main discharge valve operable by a predetermined portion of the liquid within said closed container and by a manually operable control valve; and a pressure liquid admission conduit adapted to admit liquid to said container through the inlet, whereby the air in said container is compressed above the pressure water 90 and forms a compressed air cushion; said means for controlling said main discharge valve comprising: a cylinder; a piston associated with said main discharge valve and adapted to work in said cylinder; a conduit for supplying liquid from said closed container to said cylinder; a conduit for discharging liquid from said cylinder; means for adjusting the cross section of said last-mentioned discharge conduit; and a hand operable valve for controlling the conduits associated with said cylinder, substantially as described.
